Primary Examiner — Jack Reickel*Assistant Examiner* — Keith J Wilson(74) *Attorney, Agent, or Firm* — Mitchell Law PLLC; Matthew W. Mitchell(57) **CLAIM**

The ornamental design for a portable spritzer container, as shown and described.

DESCRIPTION

FIG. 1 is a front isometric view of the portable spritzer container of the present invention;

FIG. 2 is a top plan view thereof; and

FIG. 3 is a bottom plan view thereof.

FIG. 4 is a right side view thereof;

FIG. 5 is a front view thereof;

FIG. 6 is rear isometric view thereof; and,

FIG. 7 is a left-side view thereof.

The broken line shown represents portions of a portable spritzer container and forms no part of the claimed design.
